UNITED STATES PATENT OFFICE

2,467,823

MAGNETIC CORE

Thomas D. Gordy, Pittsfield, Mass., assignor to
 General Electric Company, a corporation of
 New York

Application March 17, 1948, Serial No. 15,359

2 Claims. (Cl. 175—356)

1

This invention relates to magnetic cores and more particularly to laminated magnetic core structures for use with electrical induction apparatus such as transformers and reactors.

The laminations for magnetic cores very often are punched or cut from sheets which are produced by rolling from bars or billets of suitable ferro-magnetic material. The rolling process forms a grain structure in the sheets which normally extends in the direction in which the sheets have been rolled. It has been found that the path which offers the least resistance to magnetic lines of flux through these rolled sheets is parallel to the direction of the grain. Thus, to present a magnetic core having the lowest reluctance and being of a certain specific size it is advantageous to assemble the core sections in such a manner as to allow the magnetic flux to follow continuously the line of the grain of the ferro-magnetic core laminations.

In the normal lapped core construction it can be seen that the flux must cut crosswise of the most favorable direction at the ends of the laminations in traversing from one core leg to the next. Due to the crosswise flow of flux at the corners of the core relatively high losses occur at these points. A common way of overcoming the difficulties referred to above is to assemble the core laminations, each corner of which has been cut on the diagonal so as to provide a mitered joint. It can be seen that in a core assembled in this fashion the magnetic lines of flux run parallel in all sections of the core to the grain orientation of the laminations. Thus by the use of mitered joints core losses and excitation may be decreased.

Besides utilizing, in the construction of a transformer core, a novel mitered lamination arrangement, the laminations are of the split or divided type. Thus, both the legs and yokes of a core constructed in accordance with this invention consist of a plurality of parallel adjacent stacked punchings or laminations.

By dividing the laminations the cost of constructing a large core is reduced since the leg and yoke portions can be made from relatively narrow standard ferro-magnetic strip widths. And the necessity of using a highly expensive oversized width stock is negated. Also an improved flux path which follows the grain of the core laminations is provided. A further advantage of dividing the laminations is the consequent reduction of eddy current losses due to the narrower dimensions of each laminar section.

It is an object of this invention to provide a

2

new and improved magnetic core constructed of stacked punched laminations which presents minimum losses throughout the magnetic circuit.

An object of this invention is to provide a new and improved core construction which is simple to construct, economical to manufacture and efficient in operation.

A still further object of this invention is to provide a new and improved split lamination core construction which provides a more equitable flux density distribution between the inner and outer core sections.

The invention will be better understood from the following description taken in connection with the accompanying drawings and its scope will be pointed out in the appended claims.

In the drawing Fig. 1 is an exploded perspective view of a particular embodiment of the invention. Fig. 2 is a graph illustrating the greater efficiency of a transformer core constructed in accordance with this invention as compared with conventional core constructions. Fig. 3 is a partial front elevation of the particular embodiment of this invention shown in Fig. 1.

Referring now to the drawing there is shown therein by way of example in Fig. 1 a magnetic core 1 which has particular application to three-phase electrical apparatus. The core 1 consists substantially of three parallel legs which are each 30 constructed of two adjacent laminar stacks and of four connecting yoke pieces which are also of split construction. The illustrated construction includes one lamination layer 2 having a split leg 3 one end of which has a notch 4 which is parallel 35 to the transverse axis of the assembled laminations and an edge portion 5 which is parallel but offset from an adjacent diagonal running from the corner 6 to the outside corner 7 of the assembled lamination layer 2. A cooperating outer split 40 yoke sheet 8 has a straight or extending portion 9, which corresponds to the notch 4 of the split leg 3, and a second portion 10 which cooperates with the diagonal edge 5 of the split leg sheet 3. Similarly a split yoke sheet 11 is provided which 45 is an equivalent to the yoke sheet 8 and includes a notched portion 12 which cooperates with a notch portion 13 of the split outer leg sheet 3, both of which are parallel to the transverse axis of the assembled laminations. The remainder of 50 the mitered butt joint is provided by a surface 14 of the lamination 11 and a surface 15 of the lamination 3 both of which surfaces are parallel and offset from a diagonal running between the inner corner 16 and the outer corner 16a of the 55 assembled laminations. The remaining outer

split leg sheet 17 is provided with an extension 18 which cooperates with the notch 19 of the outer split yoke sheet 20 and an extension 21 which cooperates with a notched portion 22 of the remaining outer split yoke sheet 23. The extended portions 18 and 21 and the notches 19 and 22 are parallel to the longitudinal axis of the assembled laminations. An edge portion 24 of the leg sheet 17 mates with a corresponding edge 25 of the yoke sheet 20, both of these portions are parallel and offset from a diagonal running from an inside corner 26 to an outside corner 27. A similar edge 28 of the leg sheet 17 cooperates with a portion 29 of the yoke sheet 23, and the butt joint thus presented is parallel and offset from a diagonal running from an inside corner 30 to an outside corner 31. The other extremity of the yoke sheet 23 is provided with a mating edge surface portion 32 which is parallel to the longitudinal axis and a second portion 33 which runs diagonally from the edge portion 32 at any suitable angle. Similarly the other end of the yoke sheet 20 is provided with an edge portion 34 which is parallel to the longitudinal axis of the assembled lamination and a second edge portion 35 which runs diagonally from the edge portion 34 at any suitable angle. Cooperating with the edges of the yoke sheets 8, 11, 20 and 23 there is provided a central leg sheet 36 having extended portions 37 and 38 which mate with notches 32 and 34 of yoke sheets 23 and 20 respectively and having diagonals 39 and 40 which cooperate with a portion of the diagonals 33 and 35 of the yoke sheets 23 and 20 respectively. The remainder of the diagonals 33 cooperates with a corresponding diagonal 41 of the yoke sheet 11, and the remainder of the diagonal 35 corresponds with the diagonal 42 of the yoke sheet 8. The central leg sheet 36 is provided with two notched portions 43 and 44 which correspond to the extended portions 45 and 46 of the yoke sheets 11 and 8 respectively. These portions are parallel to the transverse axis of the assembled laminations. A suitable diagonal 47 of the yoke sheet 11 corresponds with a similar diagonal 48 of the central leg sheet 36 and a similar diagonal 49 of the yoke sheet 8 cooperates with a corresponding diagonal 50 of the central leg sheet 36.

The inner core sections comprise a leg sheet 51 having notches 52 and 53 which are parallel to the transverse axis of the assembled laminations and offset diagonals 54 and 55. The inner yoke sheet 56 has an extended portion 57 which corresponds with the notch 53 of the inner leg sheet 51 and an offset diagonal 58 which corresponds with the offset diagonal 55. The inner yoke sheet 59 similarly has an extended portion 60 which corresponds to the notch 52 and an offset diagonal 61 which cooperates with the diagonal 54 of the inner leg sheet 51. The remaining extremities of the inner yoke legs 56 and 59 have extended portions 62 and 63 respectively which cooperate with the notched portions 64 and 65 of the central leg sheet 66. Also the yoke sheets 56 and 59 have diagonal portions 67 and 68 which cooperate with corresponding diagonals 69 and 70 of the central leg sheet 66. The yoke sheets 56 and 59 have portions 71 and 72 which are parallel to the longitudinal axis of the assembled laminations and cooperate with part of edge 73 of the central leg sheet 36; the remaining portion of the edge 73 contacts the edge 74 of the central leg sheet 66. It can also be seen that the longitudinal edges 75 and 76 of the inner yoke sheets 56 and 59 cooperate with part of the

edge 77 of the outer leg sheet 3; the remainder of the edge 77 cooperates with the longitudinal edge 78 of the inner leg sheet 51. The transverse edges 79 and 80 of the inner yoke sheets 56 and 59 cooperate with the transverse edges 81 and 82 of the outer yoke sheets 8 and 11. The inner leg sheet 83 has extended portions 84 and 85 which are parallel to the longitudinal axis of the assembled laminations and cooperate with the notches 86 and 87 of the inner yoke sheets 88 and 89. The offset diagonal edges 90 and 91 of the inner leg sheet 83 cooperate with corresponding offset diagonal edges 92 and 93 of the inner yoke sheets 88 and 89 and the transverse edges 94 and 95 of the inner leg sheet 83 cooperate with part of the edges 96 and 97 of the outer yoke sheets 20 and 23. The remainder of the edges 96 and 97 contacts the edges 98 and 99 of the inner yoke sheets 88 and 89 respectively. The longitudinal edge 100 of the inner leg sheet 83 cooperates with the corresponding edge 101 of the outer leg sheet 17. The longitudinal edges 102 and 103 of the inner yoke sheets 88 and 89 butt up against the longitudinal edge 104 of the central leg sheet. It can be seen from Figs. 1 and 3 that lamination layer 105, which is contiguous to lamination layer 2, is identical in form with lamination layer 2 except it has been flipped over or rotated 180° about its longitudinal axis. Thus, the adjacent joints between contiguous laminations will be on opposite sides of the adjacent diagonal running between corresponding inside and outside corners of the assembled laminations. Therefore, the possibility of gaps being formed at the joints and the consequent increase of magnetic reluctance is substantially eliminated.

Examining the layer 2 as shown in Fig. 1 it can be seen that flux flowing in the inner core path must flow crosswise across the grain of more favorable magnetic reluctance in passing from the inner yoke sheets 88 and 89 to the central leg sheet 36. Normally there is a tendency for the flux to concentrate itself to a greater extent in the inner core section but since it must travel across the grain of the central leg sheet 36 in passing to the inner yoke sheets 88 and 89 the reluctance of the inner magnetic path is increased and a more favorable distribution of flux is achieved.

Fig. 2 illustrates a comparison between the magnetic characteristics of a core constructed in accordance with this invention and comparable cores constructed one as a split lapped core and the other merely as a lapped core. In Fig. 2 there is plotted as the abscissa of a graph the core losses in watts per pound with flux density being represented on the ordinate axis. Curve 106 represents the watts loss per pound for a particular core constructed in accordance with this invention, curve 107 the watts loss per pound for a similar split lapped core, and curve 108 the watts loss per pound for a similar lapped core. It can be seen from Fig. 2 that the core constructed in accordance with this invention, the split-lapped core, offers the highest degree of efficiency.

While there has been shown and described a particular embodiment of this invention it will be obvious to those skilled in the art that various changes and modifications can be made therein without departing from the invention and, therefore, it is aimed in the appended claims to cover all such changes and modifications as fall within the true spirit and scope of the invention.

What I claim as new and desire to secure as Letters Patent of the United States is:

1. A unitary magnetic core for three phase electric induction apparatus comprising, in combination, a plurality of flat stacked rectangular outline lamination layers each comprising three straight parallel winding legs whose ends are joined by separate straight yokes, the two outer legs and the yokes of each layer being divided longitudinally into inner and outer straight parallel lamination pieces with the width of correspondingly located pieces the same in all layers so that the two outer core legs as a whole and the core yokes as a whole are effectively longitudinally split into inner and outer parts which are separated by a longitudinal gap across which flux can pass only with difficulty, the center leg of each layer being divided longitudinally into two straight parallel lamination pieces with the width of correspondingly located pieces alternately relatively wide and relatively narrow in successive layers so that the center core leg as a whole is effectively solid and has a longitudinal lapped

joint across which flux can pass with relatively little difficulty.

2. A core as defined in claim 1 in which the joints between the ends of all the lamination pieces in each layer are substantially 45 degree mitered joints except the joints between the wider lamination piece in the center leg and the two inner yoke pieces which latter joints are square, all the joints in adjacent layers being overlapped, and all the lamination pieces being made of magnetic material having a most favorable magnetic direction coinciding with their lengthwise dimension.

THOMAS D. GORDY.
